CLAIM

The ornamental design for the battery pack for a computer, as shown.

DESCRIPTION

FIG. 1 is a rear, lower, right side perspective view of the battery pack for a computer of the present invention;

FIG. 2 is a bottom view of the battery pack of the present invention;

FIG. 3 is a rear elevation view of the battery pack of the present invention;

FIG. 4 is a front elevation view of the battery pack of the present invention;

FIG. 5 is the left side elevation view of the battery pack of the present invention;

FIG. 6 is a right side elevation view of the battery pack of the present invention;

FIG. 7 is a top plan view of the battery pack of the present invention; and,

FIG. 8 is a front, upper, left side perspective view of the battery pack of the present invention.

FIG. 1

FIG. 2

FIG. 3
